UNITED STATES PATENT OFFICE.

BERT G. DUNHAM, OF CHICAGO, ILLINOIS, ASSIGNOR, BY MESNE ASSIGNMENTS, TO
WESTERN ELECTRIC COMPANY, INCORPORATED, A CORPORATION OF NEW YORK.

AUTOMATIC TELEPHONE-EXCHANGE SYSTEM.

Application filed October 6, 1904. Serial No. 227,462.

My invention relates to automatic telephone exchange systems—that is, those systems wherein the connection between any two lines is made by automatic switches at 5 the central office, these being directed in their action by mechanism at the subscriber's station under the control of the subscriber who desired to make a call.

In the most improved type of automatic 10 telephone exchange systems prior to my invention, each subscriber's line terminates at the central office in a switching device, known in the parlance of automatic exchange working, as a first selector switch. 15 This device has, as its central moving feature, a vertical shaft capable of being lifted in steps by an electromagnet under the control of the subscriber, and after such lifting, of being rotated in an arc, carrying with it 20 contact brushes or wipers which make connection with circuits leading from the switch to other similar switches, one of which, having been selected by the operation of the first switch, may act, in its operation, selecting a third and perhaps a fourth switch, 25 and one of which, under similar control, will finally connect the line of the calling subscriber to that of the called subscriber.

In such a system as this, it is required 30 that each subscriber's line be provided with one first selector switch, and that it be of such size and provided with such an extent of vertical and rotary motion as to enable the calling subscriber to direct his line upon 35 any one of ten series of trunk lines; each of the ten series of trunk lines requires to contain a considerable number of such accessible trunks, the number usually provided being ten, and in some instances economy 40 demands that each series contain more than ten. It is therefore necessary that each first selector be a mechanism capable of selecting any one from a number of 100 or more trunk lines. The resulting size and cost of 45 the first selector switches, and the fact that one is required for each subscriber's line, causes this portion of a central office equipment of the automatic type to represent a very considerable investment. It is the object 50 of my invention to reduce this investment by providing each subscriber's line with a relatively simple and inexpensive device, which by its operation will bring into action when needed, one of a group of first 55 selectors, proceeding thereafter through the

operation of that switch and others, to set up the desired connection. While my invention requires that each subscriber's line be equipped with such a device, and that each connection involves the use of this device 60 and a smaller number of switches similar to those used in previous systems, the number of first selectors, which are expensive, is so much reduced as to render the whole installation of a given exchange much less 65 costly. This reduction of cost results from obviating the necessity of providing a first selector for each line which the office contains, and of making it necessary to provide only such a number of first selectors as is 70 required by the number of lines actually in operation at a time of maximum traffic.

Furthermore in all of the systems of automatic exchange working which have been developed up to the time of my invention, in 75 which the foregoing general principles have been used, each of the various switches involved in the establishment of a connection has been provided with a special device known as a side switch. The object of this 80 feature of the mechanism is to enable the control of the motions of the selector or connector as to its vertical and rotary shaft-motions to be effected through the agency of simple current impulses over one or the other 85 of the two wires of the line. Through the agency of this side switch one set of such current impulses over a given wire of the line may differ in result from another set, the internal connections of the switch mechanism having been changed due to the action 90 of the side switch. This side switch has been found reasonably effective in operation, but is expensive to construct and maintain. My invention, therefore, has for its 95 further object the elimination of this side switch device from some or all of the switches of automatic exchange systems, and the accomplishment of all the previously 100 possible results in a simpler manner, with fewer elements of mechanism, and a consequently decreased cost of installation and maintenance.

It is evident that to the end of accomplishing the advantages which I have first 105 described herein as an object of my invention, with reference to reducing the total investment by providing each subscriber's line with a new form of selector, those features of my invention which are pertinent to that 110

object may be selected, and may be utilized without the necessity of combining them with exactly such other selector and connector switches as are described and illustrated herein. I do not desire therefore to limit myself to the relation which I show between a system involving such an individual selector for each line and other switches which are free from side switch mechanism.

It is further evident that the arrangement of selector and connector switches within themselves so as to accomplish their vertical and rotary operations without the use of side switches, is a useful result in itself, whether or not such switches form part of an installation in which each line is provided with a special individual selector. I do not desire therefore to limit my invention to a system in which both the existence of an individual selector, and the absence of a side switch, are features, as it is of advantage to accomplish the elimination of the side switch whether or not the other advantage be adopted.

My invention is illustrated in the accompanying sheets of drawings which form a portion of this application, and in which

Fig. 1 is a plan view of the subscriber's individual selector;

Fig. 2 is an elevation of a part of that device viewed in the direction of the arrow on the line AA;

Fig. 2^a is an elevation of another part of that device, viewed in the direction of the arrow on the lines BB;

Figure 9 is a diagrammatic representation of the features of the side switch employed.

Figure 10 is a diagrammatic view showing the control of the rotary magnet armature over the private magnet armature.

Like characters refer to like parts throughout the several views.

Referring to Fig. 3, the operations performed by the subscriber in originating a call in the manner quite usual in the operation of automatic exchanges, can be understood. The talking apparatus, consisting of a receiver, transmitter and induction coil, may be connected between the vertical and rotary limbs of the lines, V and R, respectively, by the action of the hook switch, 3, in a manner well understood. Under nor-

mal conditions, that is, when the receiver is upon the hook, the bell or ringer, 4, is connected between the two sides of the line, this connection extending through the spring, 5, and the arm, 6, of the hook when the telephone is not in use. When the receiver is removed from the hook this connection is broken, and the talking contacts completed in an obvious manner. All ground connections at the subscriber's station are primarily controlled at the pair of contacts, 7, these contacts being held open as long as the receiver is on its hook, and after the receiver has been removed, until the impulse transmitting device has been put in operation.

The transmitting device acts by causing the springs 8 or 9, to engage the ground spring, 10, according to whether impulses are to be sent over the vertical or rotary sides of the line. That is, if six impulses are to be transmitted, the spring, 8, will be pressed against the spring, 10, six times, thus allowing that many impulses to flow from the central office over the vertical side of the line to ground. It is obvious from the presence of the spring, 7, that no such impulse can take place unless the receiver has been removed from its hook, and the impulse transmitter operated, for only under these conditions can the contact between springs, 7, be closed. In a similar manner an impulse over the rotary side of the line may be secured by pressing the spring, 9, against the spring, 10. It should be remembered that all selecting is done over the vertical side of the line by sending a series of impulses corresponding to the digits belonging to the number of the subscriber wanted. Each series of impulses over the vertical side of the line caused by the movements of the spring, 8, is followed by a single impulse over the rotary side of the line caused by the movement of the spring, 9.

When the hook, 3, is depressed at the close of the conversation, its arm, 11, serves to press the springs, 12, 13 and 14, momentarily into engagement with each other, thereby grounding both the vertical and rotary sides of the line through the spring, 14, and the contact, 7. The mechanical arrangement of parts is such that the springs, 12, 13 and 14, are not brought into engagement with each other as the hook rises, or while it is either depressed or elevated.

15 is the spring actuated by the ringing button, this spring normally bearing against spring, 16, and serving to hold closed the talking circuit. When, however, the ringing button is depressed, spring, 15, engages spring, 17, thereby grounding the vertical side of the line for the operation of the ringing relay in the connector switch.

The condenser, 19, is in series with the ringer, 4, with the result that the circuit

through the subscriber's telephone from the wire, V, to the wire, R, is open to direct current, although closed to alternating current, during all the time the receiver is upon its hook. Referring now to Fig. 4, the wires, V and R, from the subscriber's station are seen entering at the left of the sheet. Upon the removal of the receiver from the hook at the instrument of the calling subscriber, current will flow through the following path, energizing the relay, L; from the under-grounded pole of the battery, B, through the winding, b, of the relay, L, to the contact, 21, upon which rests the wiper, 23, to the contact, 28, and spring, 29, of the relay, CO, the wire, R, to the subscriber's instrument, through the receiver and the contact springs, 15 and 16, and the closed switch hook contacts to the vertical wire, thence to the central office, through the contact of springs, 30 and 31, the wiper, 22, and to ground at the contact, 32. As the relay, L, is energized, the attraction of its armature will break the contact between the springs, 33 and 34, and establish contact between 34 and 35. This contact establishes a circuit through the winding, a, of the relay, L, holding it energized by current from the battery, B, through that winding, the contact of 34 and 35, and to ground at contact of the wiper 24 upon 37. A circuit is also established by this latter contact from the battery, B, through the rotary magnet, RM, its series contact, 36, springs, 35 and 34, the wiper, 24, and its grounded contact, 37. As the series contact, 36, is such a one as is broken by the stroke of the armature of the magnet, RM, the circuit which has resulted will cause a succession of strokes of that armature somewhat after the manner of the familiar vibrating bell. By means of a pawl 162 best illustrated in Fig. 1 these armature motions will advance a ratchet 166 on the shaft, 38, turning the latter in such a way as to move the contact wipers, 22 to 27 inclusive, through an arc of contact pieces which also are best shown in Fig. 1. Each stroke of the armature of the magnet, RM, will advance the wipers from one set of contacts to the next, and this stepping from set to set of the contacts will continue as long as the circuit conditions are found similar in the successive steps. A feature of the operation of my system throughout is that in order that a line or a trunk may be guarded from being connected with by any switch, while it is already occupied for conversation, a conductor associated with that line and terminating in a contact piece will control the circuits to prevent connection of lines while it is grounded, but will allow them to operate to permit connection whenever it is not grounded. The contacts associated with the wire, P', in Fig. 4, have such an office. At the first step of the shaft, 38, bringing the wiper, 24, upon a contact piece of the wire, P', the ground at the contact, 37, would have been broken, and unless a ground had been found upon the contact of the trunk, P', the circuit of the magnet, RM, would have been opened and further rotation prevented. If, however, the contact of the wire, P', had been grounded, the rotary magnet would have executed another step, and step by step successively upon finding grounded contacts, would have passed to one which was not grounded, stopping the shaft as indicated. But at the same time the wiper, 26 would have left contact with 40, and would have engaged 43, which is an arc adapted to engage the wiper, 26, throughout all of its motion, except while in normal position. This engagement causes current to flow from the battery, B, through the cut-off relay, CO, the contact arc, 43, the wiper, 26, contact between springs, 35 and 34, to the grounds on contact pieces of the private wires of busy trunks. The effect is to operate the cut-off relay, CO, during such time as busy trunks are engaged, and thus by the breakage of contacts between springs, 30 and 39, respectively, and points, 31 and 28, respectively, to disconnect the line composed of wires, V and R, from the wipers, 22 and 23. The line of the calling subscriber, therefore, is thus held open at the cut-off relay, during all the time in which the wipers, 22 and 23, are passing over occupied trunk conductors. As the continuity of this circuit depends upon the grounding of the wipers, 24, the cut-off relay will release as soon as a non-busy trunk is found, and thus the line conductors, V and R, will be extended as is required. Similarly, as the actuation of the relay, L, depends upon the wiper, 24, being grounded, it will release upon the finding of the non-busy trunk. The release of its armature will break contact between springs, 35 and 34, and make contact between 33 and 34. This will ground the contact upon which the wiper, 24, rests thus making the wire, P', busy at all its contacts, and any other mechanism will be defeated from stopping with its wipers upon the trunk thus selected, because of this grounding of the private contacts. Likewise with reference to the possible stoppage of another switch upon the line composed of conductors, V and R, as they appear in connector switches, this line will be made busy by the presence of the wiper, 27, upon the arc, 44, similar in construction to the arc, 43. This will place a ground upon the private wire, P, which accompanies the calling line in its appearances in connector banks, and accomplishes the protection required.

It will now be seen that the line composed of wires, V and R, is extended, without a bridge upon it, to the wires, V' and R', and in Fig. 5, these are seen entering

at the left of the sheet. Similarly the wires, P' and D' enter, being continuations of those shown in Fig. 4. At the completion of the motion of the individual selector shown in Fig. 4, described as having selected the trunk which extends to the first selector, shown in Fig. 5, a ground was placed upon the conductor, P'. In addition to guarding the selected trunk against the incursion of another switch, this ground acts, through the contact of springs, 45 and 46, of the "off-normal" switch, to energize the relay, L', by current flowing from the battery, B. The action of this relay places the relay, VR, 10 in connection with the wire, V', and the relay, RR, in connection with the wire, R'. This is by contact of the spring, 47 with 48, and 49 with 50.

As the previously described operations 20 of the automatic selection of a trunk by the individual selector, and the just described association of the relays, VR and RR, with the two sides of the line, have taken place practically instantaneously, the result to 25 this point is that the subscriber has under his control the succeeding operations of selecting the subscriber he desires by manipulating the instrument at his station. This he does in the usual manner, in which the 30 first digit of the number is indicated by a succession of ground contacts upon the vertical wire. This succession operates the relay, VR, in as many steps, due to current from the battery, B, through its winding, 35 the contact of 48 with 47, over the wire, V, to the ground at the substation. The result of this relay operation is to make contact between 51 and 52, causing current to flow from the battery, B, through the vertical magnet, VM, 51 and 52, to springs, 53 and 54, of the magnet, DM', and to ground. The vertical magnet will thus be 40 operated a number of steps, acting through its pawl to lift the shaft, 55, stopping opposite one of the arcs of the contact bank with which the switch is equipped. As the 45 act of the subscriber's mechanism is to give one ground contact upon the rotary wire immediately after the series upon the vertical wire, such contact will cause current to flow from the battery, B, through the relay, RR, in one impulse. This by closing its contact will cause current to flow from the battery, B, through the rotary magnet, 50 RM', the spring, 56, to the contact, 52, and from 53 to 54 and ground. The action of the pawl of the rotary magnet will rotate the shaft, 55, one step, bringing its wipers, 55, 57, 58 and 59 upon the first set of three contacts in the selected arc of the bank. If there is no ground upon the private wire, PD, indicating that the trunk of the wires, V² and R², is not busy, the shaft, 55, will 60 make no further rotary motion, as its office has been fulfilled, and a trunk has been se-

lected leading to the proper thousand, as indicated by the first figure of the called subscriber's number. But if a ground is found upon the wire, PD, a further rotation of the shaft, 55, will ensue, resulting in the selection of a trunk which is not busy. This is accomplished by virtue of the control which the armature of the magnet RM' has over the armature of the private magnet PM. This mechanical connection between the respective armatures is shown in Figure 10 where a suitable extension e upon the armature m of the rotary magnet RM' engages the armature n of the private magnet PM. Thus, it will be seen that when the rotary magnet RM' is energized, the armature n of the private magnet PM will operate precisely as if magnet PM had been energized. Thus, the springs controlled by the armature of the private magnet are moved when the rotary magnet is energized precisely as if the private magnet had been energized. As this occurred at the moment of making the rotary wire contact at the subscriber's station, a circuit was established 70 from the battery, B, through the magnet, RM', through its contact, 60, springs, 61 and 62 to ground. Under these conditions, because the contact, 60, is such a one as will be broken by each stroke of the armature, rotation of the shaft would continue during the existence of those conditions. But another circuit is established at the same time from the battery, B, through the magnet, PM, contact 63, to spring, 64, thence through 75 a low resistance relay, DR, to the wiper, 59; if this wiper is engaging successive grounded contacts of wires, as PD, belonging to trunk lines which are in use, the magnet, PM, will be energized during any such successive contact, holding the circuit of the rotary magnet, RM', closed for further rotation. Upon the engagement by the wiper, 59, of a non-grounded contact, the magnet, PM, will be 80 released, breaking connection between 61 and 62, and stopping further action of the rotary magnet, RM'. 85

The relay, DR, is wound of few turns, and relatively low resistance, a practical one being about $1/2$ ohm; and when in series with the winding of the magnet, PM, the relay, DR, will not be energized. The magnet, PM, may practically have a winding of 350 to 500 ohms. 90

It has been said that the actuation of the relay, L', was the result of a circuit extending through the off-normal switch springs, 45 and 46. The contact between 46 and 45 was broken at the time of the first vertical step of the shaft, 55, but contact was made at this time between 46 and 67, establishing a circuit from the battery, B, through the relay, L', springs, 46 and 67, 65 to 66, and to ground by contact between 62 and 64 of the magnet, PM. At the beginning of 95

the rotation of the shaft, this contact of 64 and 62 was broken, but at such a time the circuit of the relay, L' continued to be established to ground through successive 5 ground contacts of the wiper, 59. It will thus be seen that the relay, L' , has been actuated from the very beginning of the cycle until the stoppage of the wipers of the shaft, 55, upon the contacts of the selected 10 idle trunk. At such time the relay, L' , released its armature, causing the line composed of the wires, V' and R' , to be extended, free from bridge, to the wipers, 57 and 58. The final release of the magnet, PM , at 15 the stoppage of the rotation, restores contact between springs, 64 and 62, replacing a direct ground upon the conductor leading through the relay, DR , to the wiper, 59. This caused no action within the switch, but 20 placed a condition of guard upon the private wire, PD , preventing an incursion of another switch upon the trunk line which has been selected.

Referring to Fig. 6, the wires, V^2 , R^2 and 25 PD , the extensions of those similarly marked in Fig. 5, will be seen entering at the left of the sheet. Upon the placing of the described ground upon the wire, PD , by the wiper, 59, current was caused to flow from 30 the battery, B , through the relay, L^2 , springs, 73 and 72, of the off-normal switch, over the wire, PD , through the relay, DR , to ground at the contact of 64 with 62, in Fig. 5. The relay, DR , being as described of few 35 turns, will not be actuated by the current which flows through relay, L^2 , which is of relatively high resistance; but the relay, L^2 , will be operated by this current, resulting in the cutting off of the wires, V^2 and R^2 , from 40 extension to the wipers, 98 and 99, and also in the connection of the relays, VR' and RR' to the lines Y^2 and R^2 , respectively. Upon the subscriber actuating his telephone, therefore, relative to the second figure of 45 the called number, contact with the vertical wire at the station will cause successive operations of the relay, VR' , because of current from the battery, B , through the winding of this relay to the springs, 82 and 77, over the wire, V^2 , and its extension to the subscriber's instrument. The resulting action on the part of the relay, VR' , will cause current from the battery, B , through the vertical magnet, VM' , the contact of springs, 50 85 and 86, and the springs, 102 and 101, to ground. The vertical magnet, VM' , will thus be actuated in as many steps as there are digits in the called figure, and through its pawl will lift the shaft, 103, as many 55 steps, stopping the wipers opposite the arcs of the contact bank containing points leading to the group of connectors in which the number of the called subscriber belongs. As 60 a rotary impulse always succeeds a series of vertical ones, such an impulse will now result and will operate the rotary relay, RR' , by current through the springs, 80 and 79, over the rotary wire to the subscriber's instrument. The resulting contact of the rotary relay will cause current to flow from the battery, through the rotary magnet, RM^2 , contact of 87 with 86, and through 102 and 101 to ground. The rotary magnet, RM^2 , will thus make one stroke of its armature, and through its pawl will rotate the shaft, 103, 70 one step, placing the wipers on the first trunk contacts of that arc. If this trunk is not busy, and by virtue thereof no ground is upon its private wire, PD' , no further action 75 will result and the desired trunk will have 80 been selected. If, however, the trunk wire, PD' , has a ground upon it, a further rotary motion will result, as follows: Because of the operation of the rotary magnet, RM^2 , and by reason of the mechanical extension 85 on its armature, the armature of the private magnet, PM' , is also actuated quite as if its core had been energized. This acted to establish a circuit through the springs of 90 the private magnet, PM' , from the battery, B , through the magnet, RM^2 , its series contact, 89, springs, 90 and 91, to ground. This contact of the rotary magnet, which is wholly independent of the relay, 95 RR' , causes it to execute a succession of strokes, each stroke resulting to open the circuit, at 89, which causes it to execute another succession of strokes, quite after the manner of the familiar vibrating bell. Such 100 strokes will succeed each other as long as the circuit conditions remain unchanged. That is, as long as the wiper, 100, continues to engage grounded private contacts of successive busy trunks. Another result of the 105 mechanical actuation of the armature of the magnet, PM' , is to extend a circuit from the battery, B , through the magnet, PM' , and its spring, 93, to spring, 92, thence through the disconnect relay, DR' , to the wiper, 100. As long, therefore, as the wiper, 100, makes 110 successive contacts with grounded points of busy lines, the magnet, PM' , will be actuated holding the circuit of the magnet, RM^2 , in rotative condition. Upon the wiper, 100, engaging a contact not grounded, the magnet, PM' , will release its armature, interrupting the circuit of the magnet, RM^2 , and stopping further rotation. By contact of 115 91 with 92, a ground is now placed upon the wiper, 100, through the magnet, DR' , thus 120 guarding the selected trunk against the incursion of another switch. The winding of the relay, DR' , is of few turns, and low resistance, the latter being practical at about $\frac{1}{2}$ ohm, and the current received by this relay, while in series with the magnet, PM' , is insufficient to operate it as the winding of the magnet, PM' , is of relatively high resistance, say about 350 to 500 ohms.

At the first motion of this second selector, 125 130

quite as was described with reference to the first selector, the spring, 73, of the off normal switch, disengages, 72 and engages 74. As the relay, L^2 , is at this time operated, it is held operated through this new contact, and that of 75 with 76 to ground of 92 with 91, or of 100 with a grounded contact point. By whichever of the three paths L^2 is operated, it remains so until such time as a trunk 10 is selected which is not busy, whereupon the final opening of its circuit allows its armature to fall away. This closes the wires, V^2 and R^2 , through the wipers, 98 and 99, and places the line in condition for the next feature of operation.

Referring to Fig. 7, the wires, V^s , R^s and PD^s are seen entering at the left of the sheet, the relays, VR^2 , and RR^2 , being bridged respectively between them and the battery. Upon the subscriber operating his instrument in reference to the third figure of the desired number, a succession of ground contacts will be made upon the vertical wire. The vertical relay responding by current from the battery, B, will make a succession of contacts between its springs, resulting in current from the battery, B, through the vertical magnet, VM^3 , the contact, 121^a, and the lever, 120^a, of the side switch, the springs, 116 and 117, of the magnet, PM^2 , springs, 107 and 106, to ground. The vertical magnet by its action will lift the shaft, 130, in as many vertical steps. The side switch which has been mentioned is a device composed of four levers, 120^a to 120^d inclusive, each adapted to make contacts, symmetrically with the others, upon one of three contact points. Fig. 9 illustrates diagrammatically the mechanical features of a side-switch adapted to carry out the operations attributed to it. In this figure the same reference characters are used, where possible, as those used in the other figures. No attempt is made in this figure, however, to illustrate associated parts which are not directly concerned in the operation of the side-switch. Thus, for example, the private magnet, PM , is shown without the contacts 114, 115, 116 and 117 which, in fact, are associated with this magnet as shown, for example in Fig. 7. The rotatably mounted shaft, 201, carries the side-switch levers 25^a, 25^b, etc. only two of which are shown, however. The associated contacts are shown at 26^a, 27^a, 28^a, and at 26^b, 27^b, and 28^b. The arm or lever, 202, having a triangular cross-section is rigidly mounted upon the shaft, 201. The private magnet PM is provided with an armature, 203, pivoted at 204 and having an arm 205, extending toward the lever, 202. A spring, 211, co-operating with a spring arm, 212, tends to cause a rotation of the side-switch shaft and its switch arms in the direction of the arrow, 213. Thus upon the energization of the private magnet PM , the

arm, 205, is depressed and this causes the tooth, 206 on the escapement arm to strike the top of the tooth, 210, on the spring member, 208, this member because of its springy characteristics being held by its engagement with lever 202 and not, therefore, being effected by the movement of the armature 203. When the arm 205 is depressed to cause the tooth 206 thereon to strike the top of the tooth 210 on the spring member 208, the spring member is thus effectively forced out of engagement with the escapement arm, 202. The face of the tooth, 206, is only slightly to the left of the face of the tooth, 210, so that the substitution of the tooth, 206, to retain the escapement arm 202 in its position in place of the teeth 210 does not permit any material rotation of the side-switch shaft due to the tension of the spring, 211. When, however, the de-energization of the private magnet, PM , permits retraction of the armature, 203, due to the influence of the spring, 214, the face of the tooth, 210, will not engage the front surface of the escapement arm, 202, and this arm and shaft will be permitted to turn to the left under the influence of the spring, 211, until it strikes the face of the tooth, 209. So, also, a subsequent energization of the private magnet, PM , will first cause the tooth, 207, to be substituted for the tooth, 209, to retain the side-switch shaft in its position, and then upon the de-energization of the private magnet the side-switch shaft will be caused to move a step further in advance. The wire, 215, which is connected with the arm, 212, passes through a hole in the rigidly supported guide, 216, and is provided with an adjustable stop, 217, by means of which the forward rotation of the side-switch shaft is limited.

The restoration of the side switches and the shaft upon which they are mounted to their normal position is brought about by the energization and subsequent de-energization of the disconnect-magnet, DM . In addition to the mechanism associated with this magnet for causing restoration of the shaft, 38, to its normal position, the armature, 218, of the magnet, DM , is provided with a catch, 219. The armature is pivoted at 220 and returned to its normal position by a comparatively stiff spring, 221. The wire, 215, which is quite springy, is provided at its end with a very thin, flexible plate, 222, this plate having a suitable opening at 223. The vertical magnet, VM , is equipped with an armature, 224, pivoted at 225, and provided at its extremity with a catch, 226. The energization of this magnet, VM , raises the armature, 224, and by means of the catch, 226, it raises also the plate, 222, disengaging it from the restraining influence of the catch, 219, and making the rotation of the side-switch shaft, 201, subject only to the

operation of the escapement associated with the private magnet, PM.

The restoration of the selector mechanism upon the energization and de-energization 5 of the disconnect-magnet, DM, restores the plate, 222, to the position shown in Fig. 7. When next this particular mechanism is 10 called into service the first energization of vertical magnet, VM, immediately releases 15 the plate, 222, from the catch, 219, and puts the side-switch under the control of the escapement associated with the private magnet, PM.

Upon the rotary contact being made at 15 the substation, as is always true after a series of vertical contacts, current from the battery, through the relay, RR², to that ground at the substation, operates the relay, RR². By this operation current flows from 20 the battery, B, through the private magnet, PM², to the spring, 108, and to ground at 106. This energizes the armature of the private magnet, PM², moving its contact springs, which act is at this time immaterial. 25 The important thing which happens is that the armature upon falling back moves the side switch levers as has been described to their second position. Upon the receipt of 30 the fourth series of vertical impulses caused by the subscriber operating his instrument relative to the fourth figure of the desired number, the vertical relay will make contacts as before, but in this instance the result will be current through the rotary magnet, RM³, contact, 122^a, lever, 120^a, springs, 35 116 and 117 of the private magnet, PM², and springs, 107 and 106 to ground. This will actuate the rotary magnet, RM³, and through its pawl the shaft, 130, in as many rotary 40 steps, moving the wipers, 132, 133 and 134, in the arcs of the contact bank before which they had been placed by the vertical motions, stopping them upon the contact pieces of the line for which the call had been 45 made. Upon the receipt of the single rotary impulse following the series of vertical impulses, current from the battery, B, through the private magnet, PM², to ground by contact of 108 upon 106, will actuate the side 50 switch a second time, advancing its levers to their third and extreme position. This serves to connect the wires, V³ and R³, serially through the condensers, 109 and 110, and the contacts of 131 with 125, and 55 126 with 124, of the calling relay, CR, to the wipers, 132 and 133.

Pressure of the ringing button at the subscriber's station will place ground upon the vertical wire, V³, again operating the relay, 60 VR²; current from the battery, B, will now flow to the calling relay, CR, contact, 123^a, lever, 120^a, springs 117 and 116, and 107 and 106, to ground. The calling relay, CR, acts to connect the terminals of the gen-

erator, G, at 127 and 129, with the wipers, 65 133 and 132, respectively by contact of the former with 124 and 125 respectively. This will send ringing current over the called subscriber's line, ringing his bell, and upon his response conversation may ensue. 70

The foregoing with reference to the action of the connector shown in Fig. 7, has been terminated upon the assumption that the line of the called subscriber was not busy, and that connection with it was not defeated by that fact. If it had been busy, 75 the operation of the connector would have been affected by the existence of ground upon the private wire, P², associated with the line of the called subscriber. In such a case instead of the line of the calling subscriber having been extended through to that of the called subscriber by the second motion of the side switch, the act of the last 80 rotary impulse would have been to pass current from the battery, B, through the disconnect magnet, DM³, springs, 114 and 115, of the private magnet, which operated in response to that rotary contact, to contact, 85 122^a, and lever, 120^a, of the side switch to 90 the wiper, 134, and thus to the ground upon the contact of the busy line. The disconnect magnet, DM³, by withdrawing its pawls from the vertical and rotary ratchets of the shaft, 130, would have permitted it to return 95 to normal position through the action of its springs and gravity.

But the calling subscriber would not have known that the connection had been defeated by these busy conditions, and would have pressed his ringing button, grounding the vertical wire. This would have operated the vertical relay, VR², by current from the battery, B, to the substation ground on the vertical wire, and as the side switch 100 levers had been returned to their normal position by the release of the connector switch, the result would have been current from the battery, B, through the vertical magnet, VM³, and the described contacts, 110 117, 116, 107 and 106, operating to lift the shaft, 130, one or more vertical steps, depending on the number of pressures of the ringing button. But the off normal switch, composed of springs, 135 and 136, would be 115 operated to close these contacts by this motion of the vertical shaft. Interrupted current induced by current from the battery B' flowing through the interrupter I which is shunted by the condenser 137 would then flow through the lamp resistance K, the off-normal switch contacts 135 and 136, contact 121^a, the lever 120^a, over the rotary wire of the line to the calling subscriber's telephone, back to the central office, over the wire, V³, and through the relay, VR², again to the battery, B'. The result is the announcement to the sub- 120 125

scriber, by a tone in his receiver, that the called line is busy, he recognizing that tone to have that significance.

Returning to the assumption that the 5 called line had not been found to be busy, and that conversation had ensued, the calling subscriber will restore his telephone to its hook at the close of the conversation. As 10 described with reference to the substation instrument, the rotary and vertical wires will be simultaneously grounded. The relays, VR^2 and RR^2 , will be actuated at the same time, connecting together their springs, 104 and 105, with the result that current 15 from the battery, B, will flow through the disconnect magnet, DM^3 , springs 105, 104, to and through the wire, PD' , the wiper, 100, in Fig. 6; the relay, DR' to ground at the springs, 92 and 91 of the private magnet, PM' , in that figure. The operation of 20 the magnet, DM^3 , in Fig. 7, will withdraw its pawls from the shaft, 130, allowing it to return to normal position. The operation of relay, DR' , in Fig. 6, which will take place 25 in series with the magnet, DM^3 , in Fig. 7, because the latter is of relatively low resistance, say about 50 ohms, will close its contacts. The result will be current from the 30 battery, B, through the disconnect magnet, DM^2 , contacts, 97 and 96, to and through the wire, PD , the wiper, 59, in Fig. 5, the disconnect relay, DR , and the ground through 35 springs 64 and 62, of the private magnet, PM . The relay, DR , although of few turns, will operate in series with the disconnect 40 magnet, DM^2 , of Fig. 6, because the latter is of relatively low resistance, say about 50 ohms. The operation of the magnet, DM^2 , and the falling back of the armature, will 45 release the second selector, allowing the shaft to return to normal position. The operation of the relay, DR , in Fig. 5, by closure of its contacts, will permit current to flow 50 from the battery, through the disconnect magnet, DM' , to ground at 94 and 95, disconnecting the shaft, 55, as soon as the magnet, DM' , is de-energized, and allowing it to 55 return to normal position. The operation of the disconnect magnet, DM' in Fig. 5, and DM^2 , in Fig. 6, to break contacts between their springs, 53 and 54, and 101 and 102, respectively, prevents false operations of the vertical and rotary relays, VR' and RR' , and VR and RR , respectively, and permits the release to be absolute.

The contact closed by the relay, DR , which resulted in the disconnection of the first selector shown in Fig. 5, also permits current to flow from the battery B in Fig. 4 through 60 the magnet DM , the wiper 25, wire D' , and the springs 95 and 94 of the relay DR to ground, thus energizing the magnet and releasing the individual selector shown in Fig. 4. This restores the individual selector to its normal position, whereupon its wipers 65

take up their normal contacts, and leave this selector in readiness to be again set in motion by the removal of the subscriber's telephone from its hook.

If a called subscriber desires to disconnect 70 his line from that of a calling subscriber at any time, he may do so by making one operation of his instrument, as if to institute a call, and then hanging up his receiver. The first described motion acts to connect the springs, 7, as shown in Fig. 3, and the second to place a ground upon both the vertical and rotary wires. This by current 75 from the battery, B, (Fig. 7) through the relay, BS , the lever, 120^b, the contact, 123^b, the springs, 131 and 125, the wiper, 132, and wire, V^4 , to ground at the subscriber's station will energize the relay, BS , and simultaneously over an analogous path will energize the relay, BR . The springs, 111, 112 and 113, will be crossed together, causing 80 current from the battery, B , through the magnet, DM^3 , to the ground thus established to operate the magnet, DM^3 , removing the pawls from the vertical and rotary ratchets 85 of the conductor shaft, 130, restoring it to its normal position through the agency of its spring and gravity.

Should this called subscriber desire to signal 90 a toll operator who had called him through the agency of a built-up trunk, after the manner of a subscriber's connection, and upon which trunk at the toll board there existed a signal associated with the rotary wire, such notice might be given by the 95 called subscriber by pressure on his ringing button. This will energize the relay BS , and the springs 111 and 112 could be made to control a local circuit containing a signal 100 or relay at the toll board which will, therefore, be actuated to notify the operator whenever the called subscriber presses his 105 ringing button.

The path of the wires, V^4 and R^4 , to the 110 called subscriber's station, is by way of his individual selector, shown in Fig. 8. This is identical with the conditions of the individual selector shown in Fig. 4, but illustrates the path of the connection over the 115 wires, V^5 and R^5 , to the called station.

In further particular reference to the individual selector as shown in Figs. 4 and 8, reference may be had to Figs. 1, 2 and 2^a, in which are shown in more exact detail the 120 relations of parts.

Fig. 1, shows the assembly of the various elements making up the individual selector switch, and is a plan view. The office of the relays, L and CO, has been described in the foregoing, and for the reason that Fig. 125 4, shows the circuit relation of these relays with reference to the magnets, RM and DM , and the other circuits involved in the system, connections by wires between the various parts of the selector switch have 130

been omitted from Figs. 1, 2 and 2^a. The shaft, 38, is carried in bearings formed of or mounted in the arm or bracket, 170, and a base, 181; the ratchet wheel, 166, is rigidly attached to the shaft, 38, by means of the screw or pin, 180, through its hub, and in engagement with the shaft. The shaft, 38, further carries the contact wipers, 22 to 27, inclusive. These are formed at their free ends in such manner as to engage the contact pieces yet to be described. Discs of rubber, fiber, or other insulating material, 182, separate the contact wipers from each other, and by suitable and usual formation insulate them also from the shaft, 38. By means of the nuts, 187, and the washers, 186, the wipers and their insulating bushings are held firmly in place so as to be rotated with the shaft, and remain in alignment with each other. The upper end of the shaft, 38, has attached to it a coiled spring, 173, the remaining end of which is attached to the arm or bracket, 170, by means of the stud, 172. The effort of this spring is always to give the shaft, 38, a rotative tendency in a clock-wise direction, as viewed in Fig. 1. Its motion in this direction is limited by contact of the projection, 167, of the ratchet wheel, 166; with the stud, 168, rising from the base plate, 181. Excess of motion in the opposite direction by the actuation of the mechanism is limited by the projection, 169, of the ratchet wheel, 166, which in its turn engages the stud, 168.

The arcs of contacts which have been referred to in the description of Fig. 4, are best shown in mechanical detail in Fig. 2, in which the base plate, 181, by means of the studs, 177, carries this portion of the structure, drawn as if viewed, with other parts removed, in the direction of the arrow on the line AA in Fig. 1. The base, 181, carries the studs, 177. The plate, 175, is supported on the studs, 177, and the layers of insulating material, 176, supported thereon, include between them the six rows of contact pieces, of which 32, 21, 37, 42, 40 and 41, are respectively the right hand pieces as shown in this view. With the exception of the arcs, 43 and 44, all of these contact pieces are of similar size to the piece, 32, and are so shaped and spaced as to correspond to the successive positions of contact of the wipers carried by the arm, 38. The arcs, 43 and 44, are of such length as to be engaged by their respective wipers, 26 and 27, when they are in any position except the normal one. The top plate, 39, serves to bind the insulating pieces and the contact pieces in a rigid manner, between itself and the plate, 175, by means of the screws, 174. The whole group of parts forms a rigid unit, which has been referred to in the foregoing as a contact bank.

Referring to Fig. 1, the magnet, RM, controlling the armature, 150, is adapted to rotate the shaft, 38. The winding of the magnet terminates at the studs, 147^b, of which there are two. The magnetic circuit is formed of the core of the magnet, its pole piece, 149, and armature, 150. The armature, 150, carries at one of its ends the pawl, 162; the latter is pivoted in the end of the armature, 150, and is adapted by the spring, 161, to be held in engagement with one or another tooth of the ratchet, 166. The other end of the armature, 150, through the agency of the insulating stud, 190, bears upon the spring, 152. The tension of this spring is such as normally to hold the armature, 150, away from the free end of the core of the magnet, and also to maintain the contact between itself and the spring, 151, this contact being designated, 36. The springs, 151 and 152, separated by the bushings, 153^a, 153^b and 153^c, are held in position upon the pole piece, 149, and therefore upon the structure of the magnet by the screws, 154. Actuation of the magnet results in drawing the pawl, 162, out of engagement with a given tooth of the ratchet, 166, and enables it to engage another. At the same time the contact, 36, is broken. Successive actuations of the armature, 150, by interrupted current or by current through its winding and the contact, 36, in series, thus causing interruptions in an otherwise continuous current, will advance the ratchet wheel, 166, tooth by tooth, as it is retained after each stroke by the engagement of the pawl, 165, which prevents its return to normal position. It is to be noted in this connection that it is the release of the armature, 150, which advances the ratchet wheel.

The magnet, DM, is formed similarly to the magnet, RM. Its pole piece, 158, forms with the core and the armature, 191, a magnetic circuit with but one gap. The armature, 191, pivoted to the pole piece by the pin, 156, carries at one free end a pivoted pawl, 159. The spring, 157, attached to the pole piece, 158, by the screws, 178, serves not only to hold the end of the armature normally away from the core, but to press the pawl, 159, into engagement with the stud, 160, carried by the base plate, 181. Upon the energization of the core of the magnet, DM, through current entering at the terminals, 147^c, the pawl, 159, will be caused to engage the hook, 192, of the pawl, 162. Upon the release of the armature, 191, from the attraction of the magnet, the pawl, 162, will be drawn out of engagement with the ratchet wheel, and will, by engagement with the pawl, 165, release the ratchet wheel entirely; and by the action of the spring, 173, the ratchet wheel, the shaft, 38, and the wipers carried by it, will return to normal position.

Having thus described my invention, what I claim as new and desire to secure by Letters Patent, is:

1. In an automatic telephone system, a central office, a metallic circuit line leading therefrom to a substation, selecting switches at the central station, a switch actuated by taking up the receiver at the substation to connect the normally disconnected line with an idle selecting switch, and means controlled at the substation to actuate the selecting switch connected with said line.
2. In an automatic telephone system, a central office, a metallic circuit line leading therefrom to a subscriber's substation, a plurality of selecting switches, an individual switch for each line, trunk lines interconnecting said individual switch and said selecting switches, and means automatically controlled by taking up the receiver at the substation to actuate said individual selecting switch to connect the calling line with an idle trunk line.
3. In an automatic telephone system a plurality of metallic circuit telephone lines, an individual switch for each of said lines, a plurality of secondary selecting switches, trunk lines for connecting said secondary selecting switches with subscribers' lines, mechanism actuated upon the removal of the receiver from the hook at a substation automatically to connect the switch arm of said individual switch with one of said secondary switches, and means controlled at the subscriber's substation for actuating a secondary selecting switch after connection with a calling line.
4. In an automatic telephone system, a metallic circuit telephone line extending from a subscriber's substation to a central office, selecting switch individual to said telephone line, secondary selecting switches and trunk lines interconnecting said individual switch and said selecting switches, and means whereby a single impulse sent over the line by the actuation of the substation switch-hook may cause the actuation of said individual switch to connect the calling line with an individual trunk line.
5. In an automatic telephone system the combination with a telephone line, of a subscriber's substation, a central office connected with said substation by said telephone line, a selecting switch individual to said line, secondary selecting switches, trunk lines leading from said individual selecting switch to said secondary selecting switches, and means automatically controlled by the initial operation of originating a call at the substation to actuate said individual selecting switch to connect the calling line with the first idle trunk line.
6. In an automatic telephone exchange system, a central office, a subscriber's substation, a metallic circuit line connecting

said subscriber's station with said central office, said line being normally open at the substation, a selecting switch at the central station individual to said line, waiting contacts in said selecting switch, trunk lines leading from said waiting contacts, secondary selecting switches connected with said trunk lines, and automatic mechanism actuated upon the closure of the line circuit at the subscriber's substation to connect said individual selecting switch with an idle trunk line.

7. In an automatic telephone system, a telephone line, contact wipers, a plurality of contact pieces, means adapting said contact wipers to engage said contact pieces, magnets adapted to control the engagement of said contact pieces, a magnet and associated mechanism adapted when said magnet is de-energized to connect said line to said contact wipers and to disconnect said controlling magnets from said line, said mechanism adapted when the associated magnet is energized to disconnect said line from said wipers and to connect said controlling magnets to said line, substantially as described.

8. In an automatic telephone system, a telephone line, a plurality of contact pieces, telephone lines connected thereto, contact wipers, magnets controlling the making of contacts between said contact wipers and said contact pieces, a magnet and associated mechanism adapted when said magnet is de-energized to connect said line to said contact pieces and to disconnect said controlling magnets from said line, said mechanism adapted when the associated magnet is energized to disconnect said line from said contact pieces and to connect said controlling magnets to said line, and means adapted to energize said magnet when a call is originated on said line, and to de-energize said magnet upon the engagement by said contact wipers of a set of said contact pieces connected to a non-busy line, substantially as described.

9. In a selecting switch for telephone lines, selecting contact pieces, a plurality of waiting contact pieces, lines leading from said waiting contact pieces, means for effecting engagement of said selecting contact pieces with certain of said waiting contact pieces, relays controlling said means for effecting engagement, conductors connecting said line to said selecting contact pieces, a switch adapted to disconnect said line from the selecting contacts and to connect said line to said controlling relays during the act of selection and to disconnect said line from said relays and connect it to said selecting contact pieces preliminary to conversation, substantially as described.

10. In an automatic telephone system, a telephone line, selecting contacts, a plurality of waiting contacts, trunk lines leading from

- 5 said waiting contacts, means for effecting the successive engagement of said selecting contacts with said waiting contacts, relays controlling said means, and a relay adapted to be energized upon the origination of a call upon said line, and upon such energization to connect said controlling relays to said line, and upon de-energization to disconnect said controlling relays from said line, and to connect 70 said line to said selecting contacts said relay being adapted to become de-energized upon the engagement of said selecting contacts with the waiting contacts of a non-busy one of said trunk lines, substantially as described. 75
- 10 11. In an automatic telephone system, a selecting switch, relays controlling said selecting switch, a telephone line, a relay adapted to be energized upon the origination of a call upon said line, and upon such energization to connect said controlling relays to said line, and to be de-energized to disconnect said relays from said line upon the selection of idle contacts in said selecting switch, substantially as described. 80
- 15 12. In an automatic telephone exchange system, a telephone line normally terminating in a selector switch at the exchange, means associated with the telephone line for operating such selector switch, and a plurality of circuits so connected to such selector switch that any one of them may be selected and connected to such telephone line by the 85 operation of such selector switch, such selector switch consisting in a rotatable shaft, a ratchet wheel mounted thereon, contact wipers carried by said shaft, contact pieces adapted to be engaged by such wipers, an actuating magnet, a pawl engaging such ratchet wheel, a pawl for normally preventing movement of said shaft in one direction, a disconnect magnet, and a catch pawl associated therewith for disengaging said pawls from said ratchet wheel. 90
- 20 13. In an automatic telephone exchange system, a telephone line normally terminating in a selector switch at the exchange, means associated with the telephone line for operating such selector switch, and a plurality of circuits so connected to such selector switch that any one of them may be selected and connected to such telephone line by the 95 operation of such selector switch, such selector switch consisting in a rotatable shaft, a ratchet wheel mounted thereon, contact wipers carried by said shaft, contact pieces adapted to be engaged by such wipers, an actuating magnet, a pawl engaging such ratchet wheel, a pawl for normally preventing movement of said shaft in one direction, a disconnect magnet, and a catch pawl associated therewith for disengaging said pawls from said ratchet wheel. 100
- 25 14. In an automatic telephone exchange system, a telephone line, a rotatable shaft, contact wipers carried by said shaft, waiting contacts associated with said wipers, electromagnetic mechanism for causing a step by step rotation of said shaft, electromagnetic releasing mechanism, a restoring spring associated with said shaft, a relay associated with said telephone line and adapted to control the actuation of said electromagnetic rotating mechanism, and a switch mechanically actuated by the movement of said shaft to disconnect said relay from the telephone line. 105
- 30 15. In a telephone system, a substation telephone and a telephone line normally open therein, a source of current, a rotatable shaft, contact wipers carried thereon, contact pieces normally engaged by said contact wipers, a relay normally connected to said line through the contact of said contact pieces and contact wipers, means adapting said relay to be energized by the closure of said line in said substation telephone, and to effect the rotation of said shaft, and means adapted to disconnect said relay from said line at the first step of the rotation of said shaft, substantially as described. 110
- 35 16. In a telephone system, a substation telephone and a telephone line normally open therein, a source of current, a line-selector, contact wipers in said selector normally connected to said line, magnets adapted to effect motions in said selector, a relay normally connected to said line and adapted to control one of said magnets, means for establishing motions of selection in said selector upon the closure of said line in said telephone and for disconnection of said relay from said line at the first of said motions, and for continuing the motion after such disconnection, substantially as described. 115
- 40 17. In a telephone system, a substation telephone and a telephone line normally open therein, an individual selector, contact wipers normally connected to said telephone line in said selector, contact pieces adapted to be engaged by said contact wipers, a source of current, a relay normally connected to said line adapted to effect successive engagement of said contact pieces with said contact wipers, and to be disconnected from said telephone line at the beginning of said successive engagements, and a magnet adapted to disconnect said line from said contact wipers during said successive engagements, substantially as described. 120
- 45 18. In an automatic telephone exchange system, a telephone line terminating in a 125
- 50
- 55
- 60
- 65

- selector switch at the exchange, means associated with the telephone line for operating such selector switch, and a plurality of circuits so connected to such selector switch
- 5 that any one of them may be selected and connected to such telephone line by the operation of such selector switch, such selector switch consisting in a rotatable shaft and contact wipers mounted thereon, a magnet
- 10 adapted to rotate said shaft, a spring adapted to return said shaft to a normal position, a magnet adapted to effect the release of said shaft for return to a normal position, a switch adapted normally to connect said line
- 15 to two of said contact wipers, a magnet adapted to operate said switch to disconnect said line from said wipers during successive engagements of said contact wipers with said contact pieces, and a relay normally
- 20 connected to said line and adapted to control the rotation of said shaft and to be disconnected from said line at the first step of the rotation of said shaft.
19. In a telephone exchange system, the
- 25 combination with a metallic telephone line normally open at the substation of a trunk circuit at the central office common to a plurality of telephone lines, and a step-by-step rotary switch started upon the closure of
- 30 the limbs of said telephone line for completing the circuit between said line and said trunk circuit, substantially as described.
20. In a telephone exchange system, the combination with a telephone line extending
- 35 in two metallic limbs from the exchange to the substation, an idle trunk circuit at the exchange adapted to the use of any one of a plurality of telephone lines, and a step-by-step rotary device having contacts for
- 40 connecting said trunk circuit and said line together and adapted to be started in rotation upon the completion of the circuit between the limbs of said line at the substation, substantially as described.
- 45 21. In a telephone system, the combination with a subscriber's station, of a pair of normally open contacts at the subscriber's station, closed during conversation to form a path for voice currents, a plurality of trunk
- 50 circuits at the exchange and a step-by-step automatic selector switch at the central office adapted to be operated to connect said line with an idle trunk circuit when said contacts are closed to initiate a call, substantially as
- 55 described.
22. In an automatic telephone system, the combination with a telephone line extending in two limbs from a substation to an exchange, of a selector switch at the exchange,
- 60 a central source of current connected in a bridge of the telephone line through normal contacts of said selector switch, a locking relay in said bridge, said relay being adapted to be initially actuated over the telephone
- 65 line and thereafter actuated over the various

busy contacts of the selector switch, whereby the selector switch is caused to rotate until an idle contact is reached, substantially as described.

23. In a telephone system, the combination with a telephone line of a line switch therefor individual to the line, a motor magnet for said line switch, a contact in circuit with the motor magnet and operated by the energization of the motor magnet, and means to complete a circuit through said motor magnet, and contacts for the operation of said line switch, substantially as described.

24. A step-by-step signal receiving device having a step-by-step element, a step-up pawl for said element, electromagnetic means to operate said pawl, a holding pawl for said element, both of said pawls being normally disengaged from said element, and both being brought into engagement with said elements upon the first actuation of said electromagnetic means and electromagnetic means to remove said holding pawl and said step-up pawl from said element.

25. In an automatic switch, the combination with a set of movable terminals, of an advancing magnet and a release magnet, a ratchet member attached to said movable contacts, a stepping pawl controlled by the advancing magnet, a retaining pawl adapted to be engaged by said stepping pawl, and a catch member carried by the armature of said release magnet and movable into engagement with said stepping pawl, the retraction of the armature of said release magnet being arranged to carry said stepping and retaining pawls out of engagement with said ratchet member.

26. In an automatic switching device, a step-by-step movable member having ratchet teeth thereon, a retaining pawl, an advancing pawl normally engaging said retaining pawl, and a catch member normally engaging said advancing pawl whereby the advancing and retaining pawls are both normally held out of engagement with said ratchet teeth, a stepping magnet and armature therefor connected with said advancing pawl, the first movement of said armature being arranged to disengage it from said catch member whereby the advancing and retaining pawls both engage the ratchet wheel teeth and a release magnet controlling the catch member.

27. In a switching device, the combination with movable ratchet teeth of a stepping magnet for controlling the movement of said teeth in one direction, and a release magnet for controlling the movement of said teeth in the other direction, a spring-pressed holding pawl, a spring-pressed stepping pawl having a portion adapted to engage said holding pawl to force the same out of engagement with said ratchet teeth, and a

member under the control of said release magnet adapted to engage the stepping pawl to move the stepping pawl and the holding pawl out of engagement with said ratchet,

5 the first movement of the stepping pawl thereafter releasing said stepping and holding pawls and permitting them to again engage the ratchet teeth.

28. In a switching device, a plurality of 10 ratchet teeth, a retaining pawl, a stepping pawl normally holding the retaining pawl out of engagement with the ratchet teeth, a catch member normally holding said stepping pawl out of engagement with said 15 ratchet teeth, a magnet controlling the stepping pawl and adapted upon its first energization to release the stepping and retaining pawls into engagement with the ratchet teeth, and upon its first deenergization to 20 move the ratchet teeth one step, and a magnet controlling said catch member and adapted upon its energization to move the catch member into engagement with the stepping pawl and upon its deenergization 25 to withdraw the stepping and retaining pawls from engagement with the ratchet teeth.

29. A step-by-step selective circuit closing device comprising a ratchet wheel, a stationary contact, a movable contact carried by 30 said ratchet wheel into engagement with said stationary contact, stepping and retaining pawls normally out of engagement with said ratchet wheel, a release magnet, an armature 35 for said release magnet controlling the movement of both said pawls out of engagement with said ratchet wheel and a stepping magnet for positively actuating said stepping pawl, and bringing both it and the retaining 40 pawl into engagement with said ratchet wheel.

30. A step-by-step selective circuit closing device comprising a step-by-step element, a stationary contact, a movable contact carried 45 by said step-by-step element into engagement with said stationary contact, a retaining pawl normally out of engagement with said step-by-step element, a release magnet, an armature for said release magnet for 50 moving said retaining pawl out of engagement with said step-by-step element when energized, and a stepping pawl for said step-by-step element maintained in inoperative position by said armature, and a stepping 55 magnet, the stepping and retaining pawls being brought into engagement with the step-by-step element by the energization of either of said magnets.

31. A step-by-step selective circuit closing 60 device comprising a step-by-step element, a stationary contact, a movable contact carried by said step-by-step element, a retaining pawl normally out of engagement with said 65 step-by-step element, a release magnet for moving said retaining pawl out of engage-

ment with said step-by-step element, a stepping pawl normally held out of engagement with said step-by-step element by said retaining magnet and normally holding said retaining pawl out of engagement with said 70 step-by-step element, and a stepping magnet for actuating said stepping pawl.

32. The combination with a ratchet, of a retaining pawl for said ratchet, a retaining magnet, an armature for said magnet adapted 75 when attracted to hold said retaining pawl in engagement with said ratchet, a stepping magnet, an armature therefor, a stepping pawl pivoted to said armature, means controlled by the armature of the retaining magnet for maintaining said stepping pawl out of engagement with said ratchet whenever the retaining magnet is in its normal position, and a spring adapted 80 when said armature of the retaining magnet is attracted to move said stepping pawl into engagement with said ratchet, whereby the ratchet may be advanced at a high speed upon the operation of said stepping magnet. 85

33. The combination with a ratchet, of a retaining pawl for said ratchet, a retaining magnet, an armature for said magnet adapted 90 when attracted to place said retaining pawl in engagement with said ratchet, a stepping magnet, an armature therefor, a 95 stepping pawl for said ratchet pivoted to said armature, a pin carried by said pawl, an arm carried by the armature of the retaining magnet adapted to engage said pin to maintain said stepping pawl out of engagement with said ratchet when the armature of the retaining magnet is in normal position, and a spring connecting said stepping pawl and stepping magnet armature, adapted 100 when the retaining magnet armature is 105 attracted to move said stepping pawl into engagement with said ratchet.

34. An automatic telephone system comprising a plurality of lines extending from substations to an exchange, fixed and movable switch contacts for said lines at the exchange, the latter contacts being normally connected to said lines, link circuits and electrically operated switching mechanism for establishing a talking circuit between the 110 movable contacts of a calling line and the fixed contacts of an idle called line, a relay for destroying the normal connection of each line with its movable switch contacts, means operative upon the engagement of said switching mechanism with said called line contacts to actuate the relay of said line by completing a circuit through one of the engaged called line contacts, and means for preventing the completion of such a circuit through the corresponding relay of the calling line. 115 120

35. An automatic telephone system comprising a plurality of lines extending from substations to an exchange, fixed and mov- 125 130

- able switch contacts for said lines at the exchange, the latter contacts being normally connected to said lines, link circuits and electrically operated switching mechanism for
- 5 establishing a talking circuit between the movable contacts of a calling line and the fixed contacts of an idle called line, a relay for destroying the normal connection of each line with its movable switch contacts, means
- 10 operative upon the engagement of said switching mechanism with said called line contacts to actuate the relay of said line by completing a circuit through one of the engaged called line contacts, and means, operative after the initial movement of said switching mechanism toward establishing said talking circuit, to prevent the completion of such a circuit through the corresponding relay of the calling line.
- 15 36. In a switching mechanism, the combination with a rotative progressively movable element and a motor magnet, a driving member actuated by the motor magnet and cooperating with the movable element, a release magnet adjacent to the motor magnet, a yieldable tripping member actuated by the release magnet and adapted when in its advanced position to co-operate with the driving member to move the latter into inoperative position, and release the same when the motor magnet is energized, and means for energizing said magnets.
- 20 37. In a switching mechanism, the combination with a rotative progressively movable member, a motor driven reciprocating member for advancing it, and a locking device for holding it, said reciprocating member and locking device being so arranged as to cooperate when the reciprocating member is
- 25 in its advance position for releasing, and a releasing device to engage one of said parts and when operated cause the simultaneous disengagement of the holding and reciprocating member.
- 30 40 45 50 55 60 65 70 75 80 85 90 95 100 105 110 115 120 125 130
38. In a switching mechanism, the combination with a rotative progressively movable element, a reciprocating member for advancing it and a magnet for operating the member, a holding device adjacent to said reciprocating member, and adapted, when the latter is in its advanced position to co-operate therewith for releasing, a releasing member and a magnet for controlling the same whereby the operation of said releasing member is caused to release both reciprocating member and holding member when the said release is operated with the reciprocating member in its advanced position.
39. In a progressively movable switch mechanism, a motor magnet having a reciprocating pawl and a release magnet adjacent thereto, a holding pawl arranged adjacent to said reciprocating pawl, said pawls being arranged so as to interengage when the reciprocating pawl is in its advanced position and a reciprocating releasing device controlled by said magnet to engage one of said parts and thus release the said switching mechanism.
40. In a switching mechanism, a rotative progressively movable element, a reciprocating driving member cooperating therewith for advancing it in one direction, and a spring for returning it in the other direction, a holding device adjacent to said reciprocating member and also cooperating therewith when the reciprocating member is in its advanced position for releasing purpose, a reciprocating tripping device to engage one of said members and when reciprocated to release both of said members, a motor magnet for moving said driving element and release magnet for operating said tripping device, said parts being arranged to operate as described.
41. In a switching mechanism, a movable member, a ratchet wheel connected therewith for moving it in one direction and a spring for returning it, a motor magnet and a release magnet, a driving member operated by said motor magnet to engage said ratchet wheel and a holding member adapted to hold said ratchet wheel in its advanced position, said driving and holding members being arranged with their holding parts in juxtaposition, and a reciprocating releasing device operated by said release magnet to engage one of said parts and when reciprocated to simultaneously release both as specified.
42. An individual switch for automatic telephone systems, comprising step-by-step mechanism including a rotatable switch-shaft, a ratchet device for giving said shaft a step-by-step motion, a spring for actuating the said ratchet device, switch contacts operated by said spring, an electromagnet adapted when energized to retract the said ratchet device, a pair of line wipers operated by said parts, a bank of trunk line terminals to be engaged by said wipers and each having a pair of line wires leading therefrom, and a source of electrical current and connections therefrom for operating purposes.
43. An individual switch for automatic telephone systems, comprising a rotatable switch-shaft, a ratchet device for giving said shaft a step-by-step motion, an electromagnet, an armature for said magnet, said armature being adapted when attracted by the magnet to retract the ratchet device, a spring-switch device adapted to be opened when the armature is attracted, said spring-switch device being also adapted to restore said armature and thereby actuate the said ratchet device, and a source of electrical current and connections therefrom for operating purposes.
44. An automatic switching device comprising a rotary shaft, a step-by-step selec-

- tive switching mechanism for operating said rotary shaft, said mechanism involving a pair of line wipers, an electromagnet, an armature for said magnet, said armature 5 when attracted being adapted to make mechanical connection with an operative part of the said step-by-step mechanism, a spring adapted to restore said armature upon the deenergizing of said magnet, means to positively release the said step-by-step mechanism, a locking dog for said mechanism also controlled by said armature, and a source of electrical current and connections therefrom for operating purposes.
- 15 45. An individual switch for automatic telephone systems, comprising a rotatable switch-shaft provided with six wipers, normal resting contacts for all of said wipers, additional contacts for four of said wipers, 20 two relatively long additional contacts for the remaining two wipers, said last mentioned contacts being substantially of the same length as the rows of additional contacts for the other four wipers, a battery 25 having one pole permanently connected with one of said long contacts, and with one or more of said wipers, and a source of electrical current and connections therefrom for operating purposes.
- 30 46. An automatic switching device comprising a rotatable switch-shaft, a ratchet-wheel on said shaft, a pawl for engaging said ratchet-wheel, an armature connected with said pawl, a magnet for operating said 35 armature, a normally closed spring-switch for restoring said armature and thereby positively actuating said ratchet-wheel, said spring-switch being connected in series with the coil of said magnet, and a source of electrical current and connections therefrom for operating purposes.
- 40 47. An individual switch for automatic telephone systems, comprising a rotatable switch-shaft, one or more wipers on said shaft, a ratchet-wheel on said shaft, said ratchet-wheel being provided with a couple of shoulders, a stationary stop adapted to engage said shoulders and thereby limit the rotation of the shaft, a pawl adapted to engage 45 said ratchet-wheel, electromagnetic and spring means adapted for operating said pawl, and a source of electrical current and connections therefrom for operating purposes.
- 50 48. An automatic switch comprising a rotatable shaft, a pair of line wipers on said shaft, a series of trunk terminals adapted to be traversed by said wipers, a ratchet device for giving said shaft a step-by-step 55 rotary motion, electromagnetic means for effecting the operation of said ratchet device, an electromagnet provided with a vibratory armature, means whereby said armature when attracted makes mechanical connection with said ratchet device, spring 60 means adapted to restore said armature when the magnet is deenergized, means to positively release said ratchet device and permit said shaft to return to its normal position, a locking dog for said ratchet device also controlled by said armature, and a source of electrical current and connections therefrom for operating purposes.
- 65 49. An automatic switch comprising a rotatable switch-shaft, a pair of line wipers on said shaft, a series of trunk terminals adapted to be traversed by said wipers, a ratchet device for giving said shaft a step-by-step rotary motion, an electromagnet provided with an armature connected to operate 70 said ratchet device, another electromagnet having an armature provided with a spring-pressed pivoted dog adapted to engage the ratchet device when the armature is attracted by its magnet, a locking dog for 75 locking the shaft against back rotation during the operation of the ratchet device, a spring for restoring said last-mentioned armature, means for releasing both the ratchet device and the said locking dog, 80 means for restoring said shaft to its normal position when thus released, and a source of electrical current and connections therefrom for operating purposes.
- 85 50. In a telephone system, the combination of subscribers' telephone lines, a battery common to said lines and normally in bridge of each line, automatic trunk-selecting and connecting apparatus allotted to said telephone lines, trunk-lines leading 90 from said apparatus, subscribers' sub-station switches for closing the line-circuits, said trunk-selecting and connecting apparatus adapted to perform a trunking operation upon the first closure of the line-circuit 95 at any calling sub-station, to extend said line circuit beyond said apparatus, automatic switches, and means for controlling said automatic switches by electrical impulses transmitted through said trunk selecting and connecting apparatus.
- 100 51. In a telephone system, the combination of a subscriber's line, a trunking switch therefor, automatic switching machinery, a circuit for first initiating the operation of 105 said trunking switch, said circuit including both sides of the line in series, and grounded line-circuits extending through said trunking switch and adapted for subsequently controlling the said switching machinery.
- 110 52. In a telephone system, the combination of subscribers' lines, selectively operated individual trunking switches for said lines, connectors each adapted to make the final connection directly with the called subscriber's line energizing circuits for enabling the subscribers to initiate the operation of their individual-switches, each of said circuits including the two sides of the line in 115 series, and grounded line-circuits for connecting

trolling said connectors, said grounded circuits including the ground between the exchange and the sub-stations of said lines.

53. In a telephone system, calling telephone lines and called telephone lines divided into groups, automatic step-by-step switching means controlled by the calling subscriber for extending connection to a called line, a circuit including both sides of 10 the calling line for initiating the operation of said automatic switching means, to select a group of the exchange, and suitable circuits extending over the calling line for controlling the operations by which the automatic switching means completes the connection to the called line.

54. In a telephone trunking system, the combination of subscribers' telephone lines, a battery common to said lines and normally 20 in bridge of each line, automatic trunk selecting and connecting apparatus allotted to said telephone lines, trunk-lines leading from said apparatus, means having vertical motion, under substation control, to select 25 groups or divisions of the exchange, and rotary motion to connect with a line in the selected group, for extending connection from the selected trunk-line in the direction of the called subscriber, and subscribers' sub- 30 station apparatus for closing the line-circuits, said apparatus adapted to be started in its selecting motion by the initial closure of the line circuit at any calling substation.

55. In a telephone trunking system, the combination of subscribers' telephone lines, trunk-lines, automatic trunk-selecting and connecting apparatus for connecting a calling subscriber's line with an idle trunk-line, actuated by the initial closure of the line to 35 40 select a trunk, means having vertical motion, under substation control, to select groups or divisions of the exchange, and rotary motion to connect with a line in the selected group, for extending connection from the selected trunk-line in the direction of the called subscriber, and a battery normally in bridge of each line.

56. In a telephone trunking system, the combination of a subscriber's line, a trunking switch therefor, automatic switching machinery having vertical motion under substation control, to select groups or divisions of the exchange, and rotary motion to connect with a line in the selected group, 50 55 for extending connection from the trunk seized by the switch in the direction of the called subscriber, a circuit for initiating the operation of said trunking switch, said circuit including both sides of the line in series, and grounded line-circuits for subsequently controlling the said switching machinery.

57. In a telephone trunking system, the combination of a calling subscriber's line, a

called subscriber's line, automatic means for 65 trunking the calling line into connection with the called line, including means having vertical motion under substation control, to select groups or divisions of the exchange, and rotary motion to connect with a line in 70 the selected group, for extending connection from the trunk seized by the switch in the direction of the called subscriber, a circuit including both sides of the calling line for initiating the operation of said automatic 75 means, a suitable circuit extending over the calling line for initiating the release of the said automatic means, and a calling mechanism for causing the vertical and rotary motion, said mechanism requiring a separate 80 actuation thereof for each digit of the called number, operative to transmit impulses by each operation.

58. In a telephone system, an automatic connector, a subscriber's non-numerical individual trunking switch, means for connecting the individual switch with the connector, release means for said individual switch under the control of the connector, and means for preventing the individual 90 switch from releasing when the connector attempts to seize a busy subscriber's line.

59. In a telephone system, a subscriber's line, a progressively movable non-numerical switch individual to said line for extending 95 a connection therefrom, means for establishing a connection to said line, an operating magnet in said switch normally connected to said line, a cut-off relay, and means for energizing said cut-off relay to disconnect said 100 operating magnet from the line when said line is calling or is being called.

60. In a telephone system, a subscriber's telephone line, a progressively movable non-numerical switch individual to said line, 105 means for establishing a connection from or to said line, a line relay individual to said line and normally connected thereto, a cut-off relay individual to said line and having relay contacts for disconnecting said line relay from said line, means for energizing said cut-off relay to disconnect said line relay when said line is used for calling purposes, and means for energizing said cut-off relay to disconnect said line relay at the time a 110 connection is extended to said line as a called line.

61. In a telephone system, a subscriber's telephone line, a progressively movable non-numerical switch for extending connection 115 therefrom, means for establishing connection to said line, a line relay individual to said line and normally connected thereto, a cut-off relay individual to said line, means for energizing said cut-off relay to disconnect said line relay from the line when said line is used for calling purposes, and means for energizing said cut-off relay to discon- 120 125

nect said line relay from the line at the time a connection is extended to said lines as a called line.

62. In a telephone exchange system, the combination of a telephone line, a bridge on said line including a relay individual to the subscriber's line and adapted to be energized over the two sides of said line in series, a

bridge cut-off relay, automatic means for energizing said relay when the line calls, controlled by the calling subscriber, and automatic means for energizing the relay when the line is called.

Signed by me at Chicago, county of Cook, State of Illinois.

BERT G. DUNHAM.
